(57) **CLAIM**

The ornamental design for a kill switch clip for a marine engine, as shown and described.

DESCRIPTION

FIG. 1 is a perspective view of an embodiment of a kill switch clip for a marine engine.

FIG. 2 is a front view of the embodiment.

FIG. 3 is a rear view of the embodiment.

FIG. 4 is a right side view of the embodiment.

FIG. 5 is a left side view of the embodiment.

FIG. 6 is a top view of the embodiment; and,

FIG. 7 is a bottom view of the embodiment.

The broken lines in the drawings illustrate portions of the kill switch clip for a marine engine that form no part of the claimed design.

1 Claim, 3 Drawing Sheets
